UNITED STATES PATENT OFFICE.

JAMES H. WALTERS AND THOMAS P. BROWN, OF HARLANSBURG,
PENNSYLVANIA.

DESIGN FOR A WINDOW-SHADE BRACKET.

SPECIFICATION forming part of Design No. 27,426, dated July 27, 1897.

Application filed May 11, 1897. Serial No. 636,112. Term of patent 14 years.

To all whom it may concern:

Be it known that we, JAMES H. WALTERS and THOMAS P. BROWN, citizens of the United States, residing at Harlansburg, in the county of Lawrence and State of Pennsylvania, have invented and produced a certain new and original Design for Shade-Roller Brackets; and we do declare the following to be a full, clear, and exact description of the invention, 5 such as will enable others skilled in the art to which it appertains to make and use the same.

Our invention has relation to a new and original design for shade-roller brackets; and it consists of a bracket of the configuration 10 and ornamentation shown in the accompanying drawing, in which the invention is illustrated in side elevation.

The leading features of the design consist in a threaded shank 1, the outer end of which is provided with a broad conical base 2, from 20 the apex of which projects a rod 3, bent downwardly and upwardly to form a lip or eye 4, thence curved downwardly and outwardly and provided with a conical head 5.

What we claim is—

25 The design for a window-shade bracket, as herein shown and described.

In testimony whereof we hereunto affix our signatures in presence of two witnesses.

JAMES H. WALTERS.
THOMAS P. BROWN.

Witnesses:

D. N. KEAST,
W. K. HUGUS.
